(57) **CLAIM**

The ornamental design for a foldable combined spoon and fork, as shown and described.

DESCRIPTION

FIG. 1 is a perspective view taken from the top, front and right side of a foldable combined spoon and fork showing my new design;

FIG. 2 is a bottom view of the foldable combined spoon and fork shown in FIG. 1;

FIG. 3 is a left side view of the foldable combined spoon and fork shown in FIG. 1;

FIG. 4 is a right side view of the foldable combined spoon and fork shown in FIG. 1;

FIG. 5 is a top plan view of the foldable combined spoon and fork shown in FIG. 1;

FIG. 6 is a rear side view of the foldable combined spoon and fork shown in FIG. 1;

FIG. 7 is a front side view of the foldable combined spoon and fork shown in FIG. 1;

FIG. 8 is a perspective view taken from the top, front and right side of the foldable combined spoon and fork shown in FIG. 1 in the fully folded configuration;

FIG. 9 is a bottom view of the foldable combined spoon and fork shown in the fully folded configuration of FIG. 8;

FIG. 10 is a left side view of the foldable combined spoon and fork shown in the fully folded configuration of FIG. 8;

FIG. 11 is a right side view of the foldable combined spoon and fork shown in the fully folded configuration of FIG. 8;

FIG. 12 is a top plan view of the foldable combined spoon and fork shown in the fully folded configuration of FIG. 8;

FIG. 13 is a rear side view of the foldable combined spoon and fork shown in the fully folded configuration of FIG. 8;

FIG. 14 is a front side view of the foldable combined spoon and fork shown in the fully folded configuration of FIG. 8;

FIG. 15 is a perspective view taken from the top, front and right side of the foldable combined spoon and fork of FIG. 1 in a partial folded configuration;

FIG. 16 is a bottom view of the foldable combined spoon and fork in the partial folded configuration of FIG. 15;

FIG. 17 is a left side view of the foldable combined spoon and fork in the partial folded configuration of FIG. 15;

FIG. 18 is a right side view of the foldable combined spoon and fork in the partial folded configuration of FIG. 15;

FIG. 19 is a top plan view of the foldable combined spoon and fork in the partial folded configuration of FIG. 15;

FIG. 20 is a rear side view of the foldable combined spoon and fork in the partial folded configuration of FIG. 15; and,

FIG. 21 is a front side view of the foldable combined spoon and fork in the partial folded configuration of FIG. 15.
